US00D685858S

(12) **United States Design Patent**
Hirayama et al.

(10) **Patent No.:** **US D685,858 S**
(45) **Date of Patent:** **** Jul. 9, 2013**

(54) **PROTECTIVE SHEET**

(75) Inventors: **Yuko Hirayama, Tokyo (JP); Atsushi Watanabe, Tokyo (JP)**

(73) Assignee: **Sony Computer Entertainment Inc., Tokyo (JP)**

(**) Term: **14 Years**

(21) Appl. No.: **29/371,925**

(22) Filed: **Jan. 30, 2012**

(30) **Foreign Application Priority Data**

Sep. 12, 2011 (JP) D2011-020662

(51) **LOC (9) Cl.** **21-01**

(52) **U.S. Cl.**

USPC **D21/333**

(58) **Field of Classification Search**

USPC ..... D21/324-333, 369, 385; D14/400, D14/401, 432, 440, 454-457, 439, 406; 273/148 B; 463/1, 29-35, 46, 47; 345/156, 345/161, 162, 168, 169, 905
